(57) **CLAIM**

The ornamental design for a chair, as shown and described.

DESCRIPTION

FIG. 1 is an isometric view of a chair;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is an isometric view of a second embodiment of the
chair;
FIG. 9 is a front elevation view thereof;
FIG. 10 is a back elevation view thereof;
FIG. 11 is a right side elevation view thereof;
FIG. 12 is a left side elevation view thereof;
FIG. 13 is a top plan view thereof;
FIG. 14 is a bottom plan view thereof;
FIG. 15 is an isometric view of a third embodiment of the
chair;
FIG. 16 is a front elevation view thereof;
FIG. 17 is a right side elevation view thereof;
FIG. 18 is an isometric view of a fourth embodiment of the
chair;
FIG. 19 is a front elevation view thereof;
FIG. 20 is a right side elevation view thereof, wherein the
left side elevation view is a mirror image;
FIG. 21 is an isometric view of a fifth embodiment of the
chair;
FIG. 22 is a front elevation view thereof;
FIG. 23 is a right side elevation view thereof, wherein the
left side elevation view is a mirror image;
FIG. 24 is an isometric view of a sixth embodiment of the
chair;
FIG. 25 is a front elevation view thereof;
FIG. 26 is a right side elevation view thereof, wherein the
left side elevation view is a mirror image;
FIG. 27 is an isometric view of a seventh embodiment of the
chair;
FIG. 28 is a front elevation view thereof;
FIG. 29 is a right side elevation view thereof;
FIG. 30 is an isometric view of the eighth embodiment of the
chair;
FIG. 31 is a front elevation view thereof; and,
FIG. 32 is a right side elevation view thereof, wherein the
left side elevation view is a mirror image.
The broken lines shown in the drawing figures are meant to
illustrate environment and form no part of the claimed
design.

1 Claim, 21 Drawing Sheets
